UNITED STATES PATENT OFFICE

112,910

DESIGN FOR A TANK VEHICLE

Howard W. Kizer, Maplewood, N. J.

Application October 14, 1937, Serial No. 72,165

Term of patent 14 years

To all whom it may concern:

Be it known that I, Howard W. Kizer, a citizen of the United States, residing at 202 Wyoming Avenue, in Maplewood, county of Essex, and State of New Jersey, have invented a new, original, and ornamental Design for a Tank Vehicle, of which the following is a specification, reference being had to the accompanying drawings, forming part thereof, in which:

Fig. 1 is a view in side elevation of a tank vehicle embodying my design.

Fig. 2 is a rear end view of the same tank vehicle, and

Fig. 3 is a top plan view of the same tank vehicle.

The dominant features of my design are shown in solid black lines.

I claim:

The ornamental design for a tank vehicle, as shown and described.

HOWARD W. KIZER.
